Primary Examiner — Cathron C Brooks*Assistant Examiner* — Sharon S Oum(74) *Attorney, Agent, or Firm* — McAndrews, Held & Malloy, Ltd.(57) **CLAIM**

The ornamental design for 3D glasses, as shown and described.

DESCRIPTION

FIG. 1 is a front perspective view of 3D glasses showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The dashed broken lines in the figures illustrate portions of the 3D glasses that form no part of the claimed design.

1 Claim, 5 Drawing Sheets
